UNITED STATES PATENT OFFICE.

THOMAS M. CONGER, OF ELYRIA, OHIO.

CUSHION HEEL.

Application filed February 17, 1920. Serial No. 359,271.

To all whom it may concern:

Be it known that I, THOMAS M. CONGER, a citizen of the United States, residing at Elyria, in the county of Lorain, State of Ohio, have invented certain new and useful Improvements in Cushion Heels; and I do hereby declare the following to be a full, clear, and exact description of the invention, such as will enable others skilled in the art to 10 which it appertains, to make and use the same.

This invention relates to boots and shoes, and more especially to those devices known as cushion heels; and its purpose is to 15 produce a lift of soft material such as rubber or rubber composition capable of being applied to the rigid or leather portion of the heel or in some cases to the sole itself, to give the article of foot wear certain advantages 20 which are peculiar to this invention such as are set forth below.

The primary object of the invention is to render the heel soft in two ways so as to make walking very easy to the wearer. To 25 this end the heel is partly pneumatic and partly cushioned, or more specifically its marginal portion is solid but of yielding or compressible material whereas its central portion contains an air pocket and protrudes 30 on its tread face beyond the margin of the tread so that when the heel is put down the weight of the wearer is first resisted by said pneumatic portion and then by the cushion portion which strikes the ground when the 35 protuberant portion has been depressed, and thus said weight is eventually sustained by all parts of the heel.

Another important object of the invention is to provide the device with anti-skid features. As set forth herein this is accomplished by dishing the marginal portion of its tread inward, or in other words inclining it outward, and forming a salient and preferably acute angle between it and the edge of 40 the lift, along that line which will be the periphery of said margin and therefore the periphery of the entire tread. When the heel strikes the ground, the pneumatic portion is first compressed, and then the cushion portions strikes the ground as above stated, but strikes the ground first along the vortex of this peripheral acute angle rather than along the entire face of the marginal portion, and such angle has a certain "clasp" 45 which prevents slipping.

A further object of the invention is to im-

prove the means for producing the air pocket within said pneumatic portion. This is accomplished by making a cavity at the center of the upper or inner face of the soft lift, 50 and entirely surrounding such cavity by a channel in such face, the channel being defined by a ridge between it and the pocket and by a margin; and then when the lift is fastened to the heel by screws or the like 55 which pass directly through the channel and are set up tight, the ridge and the margin are both drawn against the leather heel so that plural points of contact are formed between the heel and the lift and the air is 60 carefully trapped in the pocket which is produced by the flat heel and the dished or chambered inner face of the lift.

Other features of the invention will appear in the following specification which sets 65 forth one successful manner of carrying out the idea, and reference is made to the drawings wherein:

Figure 1 is a perspective view of this structure before its application to the shoe. 70

Figure 2 is a sectional view showing the structure applied and indicating in dotted lines the position of parts after the heel has come into contact with the ground.

In Figure 2 the letter H designates the 75 heel of a boot or shoe, usually made in lifts of leather nailed together, but this is for illustrative purposes only, as the invention might be applied directly to the heel portion of the sole of a boot or shoe. The structure 80 forming the subject matter of this invention is shown detached in Figure 1, and is in effect a (rather thick) lift composed of flexible or elastic material such as rubber or rubber compound, uniform in consistency 85 throughout or not as preferred, made in any suitable manner and of proper size or possibly in several sizes to fit different heels, and applied and fastened as hereinafter set forth. It might be here stated that its 90 thickness and its transverse dimensions are matters of no importance to this invention, but by preference the rubber heel tapers downward on its edge as seen, or in other words flares upward so that its upper or inner corner 1 is quite pronounced and will underlie a heel H of good size, but this corner may be pared off easily to fit smaller heels without seriously impairing the downward taper of the edge 2. For this purpose said 95 edge is preferably given a slight upright dish, and this dish may prevail across the

breast 3 of the heel, which as usual has also a transverse dish. For purposes of description we will herein call the rubber lift a heel, since it may constitute the entire heel or 5 form the lower and active portion of a leather heel. In the latter case one or two lifts of leather are removed and the rubber heel applied by passing screws 4 upward through washers 5 which are seated in sockets 6 formed in the outer face of the heel, and then forcing the screws through holes 7 through the body of the rubber and upward into the leather as shown at 8 in Figure 2; and when these screws are set up tight the 15 faces of the rubber and leather are drawn into close contact for a purpose which will be described.

The upper face of this improved heel is moulded or otherwise formed with a dished 20 or cupped center producing a cavity 10 of considerable size, around which is a ridge 11; around the ridge is a channel 12 intersected by the holes 7 through which pass the screws 4, and around the channel in turn 25 is a margin 13 which flares outward to the peripheral angle 1. The cavity is somewhat deeper than the channel, and when the screws are set up tight the faces of the margin and ridge are drawn into close contact 30 with the lower face of the heel H, and the cavity 10 becomes an air chamber or pocket, the air trapped therein being reliably retained first by the contact of the ridge with the heel H and second by contact of the 35 margin with the heel H, the outward flare of said margin making the contact between its outer edge and the heel very pronounced. If its corner is thereby urged beyond the edge of the heel as seen in Figure 2, it may 40 be pared off to produce a neat finish. Figure 1 shows five of the holes 7, but I desire not to be limited in this respect; also it is clear that other fastening means might be employed in the place of or in addition to 45 the screws, and it is quite possible that a layer of cement between the contacting rubber and leather portions would seal the air pocket absolutely tight.

The outer or lower face of the heel constitutes its tread. As seen in Figure 2, this tread is made up of an arched or protuberant central portion 20, and a marginal portion 23, the margin being dished inward from the peripheral corner or angle 21 to a line 22 where said margin unites with the central portion; or in other words, the tread comprises a central portion 20 surrounded by a channel 22, and that in turn surrounded by a margin 23 which extends to the periphery 21. Because the margin 23 flares outward and the edge 2 of the heel is of the

shape shown, a salient angle is produced at the periphery, preferably an acute angle which will have a certain cling on slippery surfaces and therefore constitutes an anti-skid feature. The sockets 6 are shown as formed in the channel 22, and this is preferred although not essential.

When the wearer places his heel on the ground, the central portion 20 (which protrudes on account of both its shape and the existence of the air pocket) first strikes the ground on the line G; pressure on the heel compresses the central portion and the air within the pocket 10 so that the parts 75 assume the position shown in dotted lines, or in other words the ground line G' rises and contacts with the peripheral angle at 21, and the anti-skid feature comes into play; and when the full weight falls on the heel, 80 it is resisted both by the pneumatic central portion and the surrounding solid or cushion portion so that the wearer has the advantages of both, as well as the advantage of the anti-skid feature. As the heel rises off 85 the ground, the parts resume their original shape.

It is to be understood that minor changes may be made so long as the spirit of the invention is retained.

What is claimed as new is:

A cushioned lift for shoe heels having its ground engaging face provided with a spherically rounded central portion surrounded by a marginal edge having greater 95 resistance to pressure than the central portion, the central portion being normally projected beyond the plane of the marginal edge and adapted to recede under pressure to the plane thereof, and the attaching face 100 being concaved to entrap an air cushion above the spherically rounded central portion of the ground engaging face and the concavity being surrounded by a channel penetrated by the lift securing means and 105 collapsible thereby to effect an air-tight contact of the attaching face of the lift with the shoe heel, the ground engaging face of the lift being divided between the spherically rounded central portion and the surrounding marginal edge by an open annular 110 channel.

In testimony whereof, I affix my signature, in the presence of two witnesses.

THOMAS M. OONGER.
